GRIDDLE CLEANER

Walter W. Quinn, Friona, Tex.

Application October 11, 1955, Serial No. 539,776

1 Claim. (Cl. 15—210)

This invention relates to new and useful improvements in culinary equipment and more particularly to a cleaner for hot griddles.

An important object of the invention is to provide a handle composed of a pair of coacting jaws in which a cleaning cloth is securely held for use in cleaning a hot griddle without danger of burning the hands and without the hands coming into contact with the grease on the griddle or cloth.

Another object of the invention is to provide a cloth holder of novel construction and including a pair of pivoted jaws having means for locking the jaws in gripping engagement with a cleaning cloth or pad.

A still further object is to provide a device of this character of simple and practical construction, which is efficient and reliable in operation, relatively inexpensive to manufacture and otherwise well adapted for the purpose for which the same is intended.

These, together with other objects and advantages which will become subsequently apparent reside in the details of construction and operation as more fully hereinafter described and claimed, reference being had to the accompanying drawings forming a part hereof, wherein like numerals refer to like parts throughout, and in which:

Figure 1 is a side elevational view;

Figure 2 is a transverse sectional view taken on a line 2—2 of Figure 1; and

Figure 3 is a bottom plan view of the cloth gripping jaws.

Referring now to the drawing in detail wherein for the purpose of illustration, I have disclosed a preferred embodiment of the invention, the numerals 5 and 6 designate a pair of substantially rectangular-shaped jaws of sheet metal or other suitable rigid material and which are pivotally connected to each other along one longitudinal edge for opening and closing movement by conventional hinge structures 7. The free longitudinal edges of the jaw are formed with teeth 8 projecting at right angles to the jaw and in opposed relation to each other to clamp a cleaning cloth or pad 9 therebetween.

Wooden or other suitable handles 10 and 11 are secured to the outer surfaces of the jaws 5 and 6 adjacent the hinged edges of the latter by screws 12.

Openings 13 and 14 are formed in the respective jaws 5 and 6 adjacent the free edges of the latter and a ball-

2

type chain 15 is anchored or otherwise suitably secured in one of the openings to extend transversely under the jaws and outwardly through the other of said openings and with the free end of the chain adjustably locked or secured in a notch 16 of a bracket 17 which is suitably secured to the outer surface of the adjacent jaw.

In the operation of the device, the chain 15 is released to permit an open swinging movement of the jaws 5 and 6 and the cleaning cloth or pad 9 is then positioned between the opposing teeth 8 of the jaw and the jaws are then closed with the cloth or pad 9 clamped therebetween, as shown in Figure 2 of the drawing. The chain 15 is then pulled tight and locked in the bracket 17 to secure the jaws in closed position. The handles 10 and 11 are then gripped in the hand of a person and the cloth or pad 9 may then be used to clean a hot griddle or other cooking utensil without danger of the hand becoming burned and without the hand coming into contact with grease on the cloth or griddle.

The foregoing is considered as illustrative only of the principles of the invention. Further, since numerous modifications and changes will readily occur to those skilled in the art, it is not desired to limit the invention to the exact construction and operation shown and described, and accordingly all suitable modifications and equivalents may be resorted to, falling within the scope of the invention as claimed.

What is claimed as new is as follows:

A holder for a flexible cleaning element comprising a pair of elongated opposite jaws having corresponding longitudinal edges pivotally connected to each other adjacent their ends for swinging of said jaws into clamping relation to a cleaning element, and releasable means for locking said jaws in clamping relation comprising a ball chain extending crosswise of said jaws intermediate the ends thereof with one end of the chain anchored to one jaw, and a notched bracket upstanding from the other jaw adjacent one end thereof, said chain extending outwardly through an opening in said other jaw and longitudinally of said other jaw into interlocking engagement with said notched bracket, and whereby said chain is interlocked to said other jaw at said opening and with said bracket to securely hold the chain in jaw locking position.
